MECHANICAL WALKING SOLDIER WITH
SHOOTING GUN

Malvina Geiser, St. Louis, Mo.

Application September 23, 1936, Serial No. 102,180

2 Claims. (Cl. 46—120)

This invention appertains to new and useful improvements in sound producing toys of the figure type.

The principal object of the present invention is 5 to provide a figure toy constructed in such a manner as to simulate in action a walking soldier.

Another important object of the invention is to provide a figure toy provided with means whereby as it is pushed will in action simulate 10 the motion of walking, while at the same time producing a noise in sound similar to that of firing a gun.

Other important objects and advantages of the invention will become apparent to the reader 15 of the following specification.

In the drawings:

Figure 1 represents a side elevational view of the toy with the handle broken away.

Figure 2 represents a fragmentary vertical sectional view through the mechanism of the toy.

Figure 3 is a fragmentary front elevational view of the mechanism of the toy.

Figure 4 is a top plan view of the mechanism shown in Figure 3.

Figure 5 is a fragmentary vertical sectional view through the cap firing mechanism of the toy.

Figure 6 is an enlarged fragmentary sectional view on the line 6—6 of Figure 2.

Figure 7 is a perspective view of one of the sliders.

Figure 8 represents a perspective view of the slider complementary to the slider shown in Figure 7.

Figure 9 is a perspective view of the cap strip feeder.

Figure 10 is a top plan view of the legs attaching frame.

Figure 11 is a fragmentary enlarged vertical sectional view through the lower portion of the mechanism frame.

Figure 12 is a top plan view of the rockable trip.

Figure 13 is a perspective view of the trip shown in Figure 12.

Figure 14 is a perspective view of a rockable plate.

Figure 15 is a top plan view of the rockable plate.

Figure 16 is a fragmentary side elevational view of the upper portion of one of the legs.

Figure 17 is a front elevational view fragmentarily showing the upper portion of one of the legs.

55 Referring to the drawings wherein like nu-

merals designate like parts, it can be seen that the toy consists of the outer shell generally referred to by numeral 5 and which consists of the torso 6, the rigidly connected head 7 and arms 8 supporting the dummy gun 9. Numerals 10—11 represent the left and right legs. A side portion of the torso 6 is provided with an opening through which access can be had to the cap roll or spool therefor and associated mechanism and this opening is normally closed by the door 12.

An elongated handle 13 inclining from the back of the figure is employed for moving the toy.

The internal mechanism of the toy consists of the frame generally referred to by numeral 14 (see Figure 3). This frame consists of the back portion 15 and the side portions 16—17.

As is clearly shown in Figure 11, a spaced wall structure 18 extends inwardly from the back wall 19 to define a pair of pockets in which the upper ends of the legs 10—11 are secured in place. The side portions 16—17 of the frame 14 are provided with vertical slots 20 as are the side portions of the wall structure 18 and through these slots as well as the upper portions of the legs 10—11 are disposed the pins 21, these pins being also disposed through the yokes 22—23 of the legs 10—11.

Between the side portions of the frame 14 is rockably supported the plate 24, which as shown in Figure 14 is of substantially Z-shape, the intermediate portion at its upper edge being provided with the V-shaped cut-away portion 25. The plate 24 is provided with the horizontally disposed finger 26 which by pin and slot connection 27 is attached to the lower end of the link 28, the upper end of the link 28 being pivotally connected as at 29 to the underlying end of the rockable trip 30.

The plate 24 is provided with a depending leg 31 which is connected by the pivotal link 32 to the upper end of the leg 11.

The upper end of the leg 10 is connected by the pivotal link 33 to the lower end of the rocker 34, the upper end of the rocker 34, which is mounted on the bracket 35, being connected to the remaining depending leg 36 of the plate 24 (see Figure 2) by a link 33'.

The rod 37 extending upwardly from the yoke 23 is pivotally attached to the underlying end of the rockable trip 30 at 29, which end of the trip is connected by a link 37' to the cap strip feeder, generally referred to by numeral 38. (See Fig. 9). This feeder consists of the side plate 40 having the right angularly disposed wall 41. The plate 40 is provided with a laterally disposed portion 42 to which the strip spring 43 is secured as 55

at 44, this strip spring being adapted to bear against the wall 41 at its upper edge. Bolts equipped with nuts generally referred to by numeral 45 are disposed through a slot 46 in the 5 adjacent front wall of the frame 14 for slidably supporting the cap strip feeder 38.

As suggested in Figure 1, the cap strip 47 is applied to the toy in the form of a roll as shown in Figure 1 and is placed on a small spool or the 10 like just inside of the door 12. This strip is fed upwardly between the spring 43 and the wall 41 and upwardly further between the front wall of the frame 14 and the hammer head 48. This hammer head 48 is secured to the upper end of 15 the inverted L-shaped hammer structure 49, the lower end of which is pivotally secured to the frame 14 as at 50. A pin 51 pivotally connects the intermediate portion of this hammer 49 to the forward end of the slider 52 and a spring 53 coiled on the anchor pin 54 at its free end bears 20 against the pin 51 for normally holding the hammer head 48 against the cap strip 47.

As is shown in Figure 6, a pair of pins 55-56 extend inwardly of the frame from the side wall 25 16 and also through the slot 57 of the slider 52 and slider 58. These sliders 52 are provided with interlapping end portions each of which is provided with the depending shoulder portion 59 into 30 which the adjacent end of the slot 57 is disposed as at 60.

A small plate 61 having a V-notch 62 therein is secured to the remaining end of the slider 58 and into this engages the free end of the spring 63 which is coiled on the anchor pin 64. This serves 35 to keep the adjacent end of the slider 58 in abutment with the lug 65 on the frame.

It can be seen in Figure 2, that the rod 66 extending upwardly from the yoke 22 of the leg 10 is connected to the opposite or remaining end of 40 the rockable trip 38 as at 67, the trip being fulcrumed as at 68 at which point the trip 38 is provided with the pair of upstanding spaced teeth 69-70 for alternate engagement and disengagement with the shoulders 59-59 of the 45 sliders 52-58.

To keep the sliders 52-58 spaced from each other on the pins 55-56, spacing members 71 are provided on these pins and between the said sliders.

Furthermore, a spring member 72 extends from one side wall of the frame 14 to bear downwardly on the upper portion of one of the sliders 52, while a second spring member 73 projects from the opposite side wall to bear downwardly on the 55 remaining slider.

In the normal position of the parts one or the other of the legs 10, 11, occupies a lowermost position in the frame 14, the trip 38 having been rocked clockwise, as shown in Fig. 2, into the limit of its movement in that direction, or, counterclockwise into the limit of its movement in this reverse direction, said trip in the described opposite limits of its movement lowering the legs 11 and 10, respectively, through the medium of the rod 37 on the one hand and the rod 66 on the other, the yokes 23 and 22 to which said rods are connected, respectively, and the pins 22 in the slots 20. The leg in its lowermost position is 70 also in its forward or starting position and the other leg is inclined rearwardly.

In Figs. 2 and 3 the leg 11 has been shown as occupying its lowermost and forward position in which it is, in effect, the longer.

The operation will now be described starting

with the parts in the position shown in Figs. 2 and 3.

The handle 13 is held in the hand and the toy is pushed forwardly with the longer leg 11 engaging the ground or floor and sustaining partially the weight of the toy. This procedure swings the leg 11 rearwardly on its pin 21 thereby pulling links 32 forwardly and rocking the plate 24 counterclockwise. Plate 24, through the pin and slot connection and the link 28 swings the 10 trip 38 counterclockwise on its fulcrum 68. Trip 38 lifts rod 37 and lowers rod 66, thereby lifting leg 11 in the frame 14 and lowering leg 10. Simultaneously with rearward swinging of the leg 11 and lifting thereof, leg 10 is swung forward 15 as it is lowered, the described swinging of the plate 24 effecting this operation through the links 31', rocker 34, and link 33. Leg 10 now bears on the ground and leg 11 is lifted in the frame 14 and inclined rearwardly. During the counterclockwise movement of the trip 38, the link 37' pushes the strip feeder 38 upwardly to correspondingly feed the caps 47 and to position a cap in front of the hammer head 48. Coincidentally with the caps positioning operation, the tooth 25 69 on the trip 38, engaging shoulder portion 59 on the slider 52, is swung to retract said slider 52, thereby retracting the hammer head 48 against the tension of the spring 53, said tooth 30 69 wiping past said shoulder portion 59 thereby releasing said hammer head for striking movement under the influence of the spring 53. The hammer head 48 in its striking movement returns the slider 52 to advanced position as will be clear. The reaction of the spring 53 tensions the slider 52, trip 38 and leg 11 against the described movements thereof until the slider 52 is released. During the described swinging of the trip 38 and the tooth 69, the tooth 70 is swung against the depending shoulder portion 59 of 40 slider 58 rocking the same counterclockwise on the pin 55, the slot 60 in said slider 58 permitting such swinging, and against the tension of the springs 72, 73 until said tooth 70 wipes past said shoulder portion 59 and snaps behind the same, 45 said slider 58 at this point being rocked clockwise by the springs 72, 73 into the limit of its movement in this direction as determined by the pin 55 and slot 60. In this position of the tooth 70 and slider 58, the trip 38 is tensioned against 50 return clockwise movement and the leg 10 against rearward movement first by the spring 63 and second by the springs 72, 73. The leg 10 is now swung rearwardly on its pin 21 in the same manner as described with reference to leg 11. Such 55 swinging of the leg 10 pulls link 33 forwardly thereby swinging rocker 34 counter-clockwise. Rocker 34 pulls link 33' rearwardly and returns plate 24 clockwise to starting position. Plate 24, through link 32, swings leg 11 forwardly and through link 28 rocks trip 38 clockwise to starting position. Trip 38, through link 37, lowers leg 11 and through link 66 lifts leg 10 and simultaneously, through link 37', lowers trip feeder 38. 60 Tooth 70 pulls slider 58 forwardly against the tension of the spring 63 during which operation tooth 69 wipes under shoulder portion 59 of slider 52 swinging the same upwardly on fulcrum 66, the slot 60 in slider 52 permitting this operation, and slider 52 lifts slider 58 upwardly on fulcrum 65 66, the slot 60 in slider 58 permitting this operation. This lifting of slider 58 permits the tooth 70 to disengage shoulder portion 59 thereof and swing under the same. As soon as tooth 69 wipes past shoulder portion 59, on slider 52, the latter 70

together with the slider 58 are returned downwardly by the springs 72, 73 and tooth 69 snaps in front of shoulder portion 59 on slider 52. As soon as tooth 70 disengages shoulder portion 59 of slider 58, the latter returns backward into engagement with lug 65 under the action of the spring 63 to its normal position. The parts are now in the position shown in Figs. 2 and 3 with the leg 11 again positioned for operation as previously described.

10 While the foregoing specification sets forth the invention in specific terms, it is to be understood that numerous changes in the shape, size and materials may be resorted to without departing from the spirit and scope of the invention as 15 claimed hereinafter.

Having described the invention what is claimed as new is:

20 1. In a toy having the form of a human figure, a torso part, a handle extending rearwardly from the torso part for propelling the figure along the ground, a pair of legs adapted to be engaged with the ground, means to mount said legs on the torso part for alternate swinging movement rearwardly by engagement with the ground, and for independent lengthwise movement upwardly and 25 downwardly relative to the torso part comprising axis members vertically slidable on said torso part, means operative by rearward swinging of one leg to swing the other leg forwardly and including a rocker, means operative by said rocker 30 to move the rearwardly swinging leg upwardly and the forwardly swinging leg downwardly simultaneously with such swinging thereof and including a lever pivoted intermediate its ends, a pair of rods operatively connecting opposite ends 35 of said lever to said legs, respectively, a hammer for impacting caps, and a slide for feeding strips of caps to the hammer, said hammer and slide being operative under control of said lever alternately.

MALVINA GEISER.

wardly and the forwardly swinging leg downwardly simultaneously with such swinging thereof and including a lever pivoted intermediate its ends, a pair of rods operatively connecting opposite ends of said lever to said legs respectively, 5 and detonator mechanism operative under control of said lever.

2. In a toy having the form of a human figure, a torso part, a handle extending rearwardly from the torso part for propelling the figure along the ground, a pair of legs adapted to be engaged with the ground, means to mount said legs on the torso part for alternate swinging movement rearwardly by engagement with the ground, and for independent lengthwise movement upwardly and 10 downwardly relative to the torso part comprising axis members vertically slidable on said torso part, means operative by rearward swinging of one leg to swing the other leg forwardly and including a rocker, means operative by said rocker 20 to move the rearwardly swinging leg upwardly and the forwardly swinging leg downwardly simultaneously with such swinging thereof and including a lever pivoted intermediate its ends, a pair of rods operatively connecting opposite ends 25 of said lever to said legs, respectively, a hammer for impacting caps, and a slide for feeding strips of caps to the hammer, said hammer and slide being operative under control of said lever alternately. 30
